(57) **CLAIM**

The ornamental design for a holder of a detection device for endoscope, as shown and described.

DESCRIPTION

FIG. 1 is a front perspective view of a holder of a detection device for endoscope showing my new design;

FIG. 2 is a rear perspective view thereof;

FIG. 3 is a front view thereof;

FIG. 4 is a rear view thereof;

FIG. 5 is a top plan view thereof;

FIG. 6 is a bottom plan view thereof; and,

FIG. 7 is a right side view thereof, the left side view being a mirror image of FIG. 7.

The broken lines illustrate portions of the holder of a detection device for endoscope and form no part of the claimed design.
